UNITED STATES PATENT OFFICE

ALVIN P. BARNES, OF MINNEAPOLIS, MINNESOTA, ASSIGNOR TO SERV-RITE CORPORATION, OF MINNEAPOLIS, MINNESOTA, A CORPORATION OF DELAWARE

DESIGN FOR A FRUIT HOLDER

Application filed February 21, 1931. Serial No. 38,772. Term of patent 3½ years.

To all whom it may concern:

Be it known that I, ALVIN P. BARNES, a citizen of the United States, residing at Minneapolis, in the county of Hennepin and State of Minnesota, have invented a new, original, and ornamental Design for a Fruit Holder, of which the following is a specification, reference being had to the accompanying drawing, forming part thereof.

The figure is a perspective view of a fruit holder showing my new design.

I claim:

The ornamental design for a fruit holder, as shown.

ALVIN P. BARNES.
